[57] CLAIM

The ornamental design for a dispensing cap for an eyedrop bottle, substantially as shown and described.

DESCRIPTION

FIG. 1 is a front elevational view of a dispensing cap for an eyedrop bottle, showing my new design, the back elevational view being substantially a mirror image thereof;

FIG. 2 is a side elevational view thereof, the opposite side being substantially a mirror image thereof;

FIG. 3 is a top plan view thereof;

FIG. 4 is a bottom plan view thereof; and

FIG. 5 is a cross-sectional view taken along line 5—5 of FIG. 2.

FIG. 1

FIG. 2

FIG. 3

FIG. 4

FIG. 5
